UNITED STATES PATENT OFFICE.

KENNEDY DOUGAN, OF MINNEAPOLIS, MINNESOTA.

TYPE-WRITER.

1,152,495.

Specification of Letters Patent.

Patented Sept. 7, 1915.

Application filed December 27, 1913. Serial No. 809,000.

To all whom it may concern:

Be it known that I, KENNEDY DOUGAN, a citizen of the United States, and resident of Minneapolis, in the county of Hennepin and State of Minnesota, have invented certain new and useful Improvements in Type-Writers, of which the following is a specification.

This invention relates to typewriters.

10 The object of the invention is to provide a small, light typewriting apparatus, adapted to write upon a sheet of paper laid flat upon a desk or table.

15 A portion of the apparatus is to be set directly upon the paper to be written on; the remainder of the apparatus, *i. e.*, the printing devices or type-carriers, are to be attached to and operated by the operator's fingers.

20 In order that the invention shall be fully understood, reference is to be made to the accompanying three sheets of drawings, in which:

25 Figure 1 is a side elevation of a preferred form of finger-carried printing device. Fig. 2 is a vertical sectional view, on a line II-II of Fig. 1. Fig. 3 is an enlarged horizontal section of two associated type-bars, their guides, the connecting gear, and 30 a spring. Fig. 4 is an enlarged vertical section of one of said type-bars. Fig. 5 is a horizontal section of the frame of the device shown in Fig. 1, omitting the parts within said frame. Fig. 6 is a diagram showing 35 the arrangement of type-bars. Fig. 7 represents a simultaneous impression of all the type carried by one type-carrier. Fig. 8 is a top view of a machine which is adapted to guide the type-carriers in writing upon flat 40 sheets of paper. Fig. 9 is a transverse sectional view on a line IX-IX of Fig. 8. Fig. 9^a is a detail view of an overthrow-check. Fig. 10 is a central vertical section of certain details, on a line X-X of Fig. 45 8. Fig. 11 is a plan diagram of the machine shown in Fig. 8, with an inking-pad in front. Fig. 12 is a top view of a modified typewriter which has no carriage. Fig. 13 is a cross sectional view on a line 50 XIII-XIII of Fig. 12, showing an engaged type-block. Fig. 14 is an end elevation without the type-block. Fig. 15 is a front elevation of the ink-pad. Fig. 16 is a sec-

tional detail view of one line-spacing device, viewed in direction of arrow, Fig. 14, but 55 showing all the levers in operative position. Fig. 17 is a vertical sectional view of a two-series type-carrier adapted for this species of typewriter.

Referring in detail to the drawings: The 60 frame, or case, of a carrier comprises integral ends 1 and top 2, and removable side-plates 3. On the top portion 2 is attached a finger-clip, comprising, as shown here, two U-shaped pieces 4 and 5, both of re- 65 silent sheet metal. The piece 4 has ears 6 which firmly engage the sides of an inserted finger, while the piece 5 receives the top of the finger. In the frame or case 1-2-3 are two rows or series of longitudinally 70 75 slidable type-bars 7, each of which bears upon its lower end a type 8. The number of type-bars to a row may vary from three to seven, according to the sizes of types employed. Were all the type in said carrier impressed 80 at once upon a flat sheet of paper, the impressions would appear as shown in Fig. 7, for example. But the device is so constructed that the type are selectively projected from the case for successive use as will 85 be described hereinafter.

The type-bars 7 are guided in their movements by small ears 9, struck in from the side plates 3, and by longitudinal bars 10, fastened to the end portions 1. Each type-bar 7 is preferably U-shaped in right section, and its base portion is provided with an interior rack, or with a row of perforations 11 by which it becomes a rack in function. Thus the bars 7 are rack-bars as well 90 as type-bars. Each opposed pair of rack-bars are geared together, preferably, with a pinion 12. The series of pinions 12 are separately rotatable on a shaft 13 whose ends are fixed in the frame ends 1. Each pinion 95 12 is yieldably held in a normal position, *i. e.* that in which the two associated rack-bars are at the same height, or in line, as shown in Fig. 2, by a spring 14, depending from a rod 16 and connected to an eye 17 100 on the pinion hub, by a fine chain or cord 18, which latter will obviate injury to the spring where the movement of the pinion is half a turn or more.

Desirably the type blocks 8 are either 105 loosely connected to the respective bars 7,

or in a manner to permit of limited rocking motion in all directions. Fig. 4 shows a type block provided with a half-ball head 19, which fits rockably in a socket milled in the end of the bar 7. A thin flat torsion spring 20 has its lower end fixed in a kerf in the head 19 and its upper T-shaped end has ears 20^a which rest on lugs 21 struck in from flanges 7^a, there being two pairs of said lugs, between which pairs the said spring portions 20^a are loosely inserted. Thus the spring 20 supports the type-block 8 and also returns it to normal alinement after any deviation therefrom. Each type-bar is provided on its outer face with a stud 22, which is flush with the side plate 3 adjacent. To permit movement of the studs 22 both up and down, the side plates 3 are made with slots 23, the lower ends of which are flared, thus providing each of said plates with a row of prongs 24, which normally extend nearly to the faces of the type, and terminate in a plane parallel to that of said faces. It is obvious that by depressing the carrier-frame bodily, and at the same time supporting any stud 22 as by a post or vertical pin, the pinion engaged with the bar 7 carrying said stud, will be turned and will drive down the other bar 7 to which it is geared; the motion of the latter being double the downward motion of the frame. This type-carrier may be employed in connection with any suitably devised machine having means for accurately registering a type-block with a point on a sheet of paper, and means for engaging any of the studs 22 when the carrier is positioned by the operator and depressed. In Figs. 8 and 9 is shown a machine that is adapted for using said type-carriers to write upon sheets of paper laid flat upon a desk or table, there being no platen. This machine is very small and light, and may be constructed almost entirely of sheet metal. The base 26 of said machine is a rectangular sheet metal plate, having a breadth greater than that of commercial or legal size paper. It is held in position upon a sheet of paper 27 by short pins 28 which are permanently secured to the base. 29 is a longitudinal slot, through which one line at least of writing will be visible. 30 is a carriage, which travels longitudinally upon the base 26, and is supported by four anti-friction rollers 31, three of which are shown in Fig. 9. The front side of the carriage is held from rising by a continuous angular flange 32 on the base. The rear side of the carriage is held from rising by a similar flange 33. The carriage is held from contact with the inner face of the front flange 32, by a downturned lip 33^a on the rear flange 33.

The carriage is provided with a square opening 34, the size of one type-block, and registering with the slot 29 in the base 26.

Over and around said opening 34 is a low hopper shaped guide 36, whose inclined inner walls 36^a direct a type-block into said opening. At each side of said guide is a post 37, having the same thickness as one of the type-bar studs 22, and its upper end 37^a at such a height that when a stud 22 is placed thereon and the carrier depressed, a type will run down through the opening 34 and strike the paper 27 with the proper length of stroke. Each post 37 is provided on its upper end with an outwardly and upwardly inclined lip 38.

To print a given letter, the type-carrier is held with the rows of type normal to the slot 29 in the base; the carrier-slot 28 opposite such letter is placed over the right or left hand post 37, according to which row the given letter belongs; the carrier is depressed; a stud 22 strikes the lip 38, which guides the stud to the top of the post 37; the carrier continues downward, the proper type-bar 7 is run down through guide 36 and opening 34 and prints a character upon the paper. When the carrier is raised, the spring 14 that was tensioned by the said movements raises the type-bar just used and lowers its mate, thereby re-positioning the type-bars in the carrier. There may be six of said carriers, three for each hand. A sight opening 39 (Fig. 8) in the carriage may be cut at the left of the type-hole 34, so that the next to the last character printed may be seen by the operator.

The carriage is automatically given a step-by-step movement during each upward movement of a type-carrier. This is effected by means initially actuated by each downward movement of a type-carrier, or by a thumb or finger pressing upon a spacer-key 105 and striking-plate, or key-plate 40. Said key-plate 40 is so positioned that its portion 40^a will be struck by one or more of the prongs 24, in the downward stroke of a type-carrier in any operative position, toward or from the operator, or right and left. Said key-plate is pivoted on pins 41, 42 which turn in bearings 43, on the carriage. It is pressed upward by a torsion spring 44, on pin 42, and engaging a lug 46.

Integral with key-plate 40 is a rearwardly extending arm 47 which carries an arc gear 48, which meshes with a pinion 49, on a shaft 50 journaled in bearings 51, 52. Pinion 49 carries a pawl-arm 53 on which is a driving pawl 54 which is spring-pressed upon a ratchet wheel 56 on said shaft. Secured to ratchet-wheel 56 is a worm 57. If the worm and ratchet wheel are keyed on the shaft, the pinion will be loose, or the pinion may be keyed, with the worm and ratchet wheel loose. An idle pawl 58 prevents the ratchet wheel from turning backward. The pawl 54 turns the ratchet wheel during the upward motion of the gear-arm 130

47, leaving the worm 57 motionless during the down stroke. As shown, the pinion 49 will be turned exactly half a revolution at each operation. Due to inertia of motion, 5 the ratchet and worm might be over-thrown by the pawl 54, and to prevent this a detent 59 is mounted on the gear arm 47. To receive said detent two notches 60 are cut in one end of the worm hub 57^a and diametrically opposite each other. The detent serves 10 two purposes, as it not only limits the turn of the worm to the exact turn imparted by the pawl, but forms a stop to the upward motion of the gear 48 and key-plate 40. 15 The worm 57 engages notches 61 in a longitudinal rack bar 62, whose ends are provided with pivots 63 which are held by standards 64 on the base plate 26. A lever 66 is mounted on one of the pivots 63, for 20 turning the rack-bar 62 which is held at a normal angle by leaf springs 67 (Fig. 9) bearing thereon.

To move the carriage to the left, depress the lever 66, thereby turning the rack-bar 25 out of engagement with the worm 57, and slide the carriage by a finger placed against one of the posts 37. Then register the worm with a notch 60 and return the rack-bar to normal position. To space the carriage forward, 30 depress the key 40 once for each space. When printing, one or more prongs 24 of each type-carrier will depress the portion 40^a of the key-plate 40, and when the carrier is lifted the spring will step the carriage for the next character, as described. 35 To space between lines, the machine is bodily raised and moved forward by means of a device shown in Fig. 16 and presently described.

40 Figs. 12, 13 and 14 illustrate a flat-sheet typewriter in which no carriage is provided. As a substitute therefor, a series of stationary type-bar guides are arranged across the frame or base, there being as many type-spaces between said guide as there are characters in the longest line of writing. The type-carriers are like that hereinbefore described, but the studs are omitted and the type-bars are actuated selectively by being 45 directly pressed upon said type-bar guides. The frame of the typewriter is flat, rectangular and horizontal. It comprises end pieces 125 and two upturned flanges 127 along its longitudinal outer edge. Said 50 frame is provided with pads 128, of soft rubber or other good friction material. These pads rest upon the sheet of paper 129 and prevent the frame's slipping thereon. Integral with or secured in said frame are 55 a series of upturned transverse ribs 130, hereinafter called guides. These guides are spaced apart the diameter of one type-block, and are of such length as to receive a guide-lug 131 on a type-carrier 132 in any position 60 of the carrier, the carrier having such a lug

at each end of each of the two series of type-bars 133.

134 are two longitudinal guiding-flanges, which are spaced apart the diameter of a type-block, and guide the type-blocks at the 70 ends of their downward strokes. The flange 134 nearest the front is made as low as possible, so that the operator can see the words already written by looking obliquely downward on the line of the arrow, Fig. 15. The 75 slots 137 have no function, but reduce the weight of the frame. The outer flanges 127 serve to brace the transverse guides 130. Rising from the inner end of each transverse guide 130 is a narrow pin or post, 138, having 80 vertical inner and outer edges, except that the upper portions of the inner edges are beveled as shown at 138^a. The opposed pairs of members 138 form abutments and guides, in which the mates of the type to be 85 used are inserted.

In order to leave the writing visible, a ribbon should be omitted and the type be inked upon a large pad as 139, which is shown in Fig. 14 in front of the typewriter. 90 The bottom of the case of said pad is provided with narrow runners 139^a which slide upon the paper at the margins thereof.

To cause the lines to be printed in parallelism, any suitable construction may be resorted to. A very simple device for the purpose is here shown, consisting of two sets of pointed stepping levers 140, 141, 142, one set at each side or end of the frame, and having fulcrums positioned somewhat forwardly of the center of said frame. Said fulcrums 147 are held by the frame ends 125. Each set of levers is mounted on a main lever 143 having an operating handle 144. Said pointed levers are of three lengths, and are adapted respectively to shift the frame a single space, a double or a triple space. As shown, all three levers are pivoted on one pin 146 which is carried by the main lever 143 below its fulcrum, 147. On the main lever are three stops 148, which prevent the respective stepping levers from turning on the pivot 146 in one direction, but permit them to be turned in the other or rearward direction. If all three levers of each set 110 were left in operative position, when the handles 144 are drawn forward the longest levers 142 would engage the paper first and shift the machine a triple space. Hence the operator will first turn up the two levers not to be used, upon their pivot 146 at each side of the frame, thereby making them inoperative. Each lever 140, 141, 142 is provided with a leaf spring 149 which by pressing on the associated stop 148 holds its lever 115 yieldably in extended position when said lever is free of the paper. Fig. 16 shows very well the relative operative positions of the levers 140, 141, 142 and their relative 120 lengths. When the handles 144 are drawn 125

95 of the carrier, the carrier having such a lug 131 on a type-carrier 132 in any position 130 of the carrier, the carrier having such a lug

forward, the levers 140 penetrate the paper and engage the wood beneath it, and as they turn backward the main pivots 147 lift and carry the frame forward the proper distance, at each end thereof, so the lines of writing will be parallel. The handles 144 are then returned to the normal position, during which movement each pointed lever 140 turns backward on pivot 146, thereby 10 tensioning its spring 149, until free of the paper, when it is immediately re-extended by said spring. When the handles 144 are released said levers will fall back upon the paper to the starting position. The main levers 143 require no stops, because no matter how far they are turned, the machine will be shifted the right distance only.

It will be understood that in writing with this apparatus the operator inserts the type bearing the proper characters in the successive points of the longitudinal slot between the guide-flanges 134. The details of the operation have already been described.

Having described my invention, I claim, 25 and desire to secure by Letters Patent:

1. In a typewriter, a frame adapted to be set upon a flat sheet of paper, means held by said frame for guiding type in successive positions to write a line, and a manually 30 carried frame, provided with a plurality of type.

2. In a typewriter, a frame adapted to be set upon a flat sheet of paper, means held by said frame for guiding type in successive 35 positions to write a line, a manually carried frame, provided with a plurality of type, and means for selectively printing with said type, said means comprising a member associated with the type-guide held 40 by said frame.

3. In a typewriter, a multicharacter printing device adapted to be carried by and upon a finger of the hand; a frame adapted to be set upon a flat sheet of paper; and 45 means mounted on said frame for guiding and selectively operating the type when the said printing device is depressed in certain relative positions to said guiding and selective operating means.

50 4. In a typewriter, a base adapted to be set upon a flat sheet of paper, said base having a slot therein parallel to the lines of writing; a carriage movable on said base parallel to said slot, a type-guide and an 55 abutment carried by the carriage, a manually carried frame, a series of separately movable type carried by said frame, and projections on said type, adapted for engagement with said abutment.

60 5. In a typewriter, a base adapted to be set upon a flat sheet of paper, said base having a slot therein parallel to the lines of writing; a carriage movable on said base parallel to said slot, means for shifting the 65 carriage step by step, said means comprising

ing a movable element positioned to be actuated by a type-carrier, a manually carried type-carrier provided with means for actuating said element, and a series of movable type-bars in said carrier.

6. In a typewriter, a base adapted to be set upon a flat sheet of paper, said base having a slot therein parallel to the lines of writing; a carriage movable on said base parallel to said slot, means for shifting the 75 carriage step by step, said means comprising a downwardly movable plate positioned to be actuated by depression of a type-carrier, a spring bearing said plate upwardly, a manually carried type-carrier provided with means for actuating said plate in its printing movement, and a series of movable type-bars in said carrier.

7. In a typewriter, a carriage, a worm mounted upon the carriage, a base, a rack-bar supported by the base and meshed with said worm, a movable plate mounted on the carriage, means to turn said worm by movement of said plate in one direction, a spring to move said plate in the opposite direction, 90 a type-guide mounted on the carriage, a manually carried type-carrier provided with means for actuating said plate, and type-bars in said carrier.

8. In a typewriter, a carriage, a type-guide adapted to receive a single type, a pair of posts arranged at opposite sides of said guide, upon the carriage, a type-carrier comprising two series of type-bars each relatively movable therein, lateral studs on said 100 type-bars, each stud being adapted to engage one of said posts, means on the type-carrier to engage said posts for guiding the studs to meet said posts, and means whereby when the type-carrier is depressed with any type-bar stud upon one of said studs, a different type-bar will be thrust down through said type-guide.

9. In a typewriter, a frame adapted to be set upon a flat sheet of paper, said frame 110 having an opening therein parallel to a line of writing; longitudinal type-guides along the sides of said opening, a series of combined type-guides and abutments arranged along said opening and spaced apart to correspond with spacing of letters in a line, a manually carried type-carrier, comprising two series of type-bars movably mounted therein, and type on said type-bars; said abutments and guides being adapted to uphold one type-bar only when the type-carrier is depressed in proper relative position.

10. In a typewriter, a frame adapted to be set upon a flat sheet of paper, said frame having an opening therein parallel to a line of writing; longitudinal type-guides along the sides of said opening, a series of combined type-guides and abutments arranged along said opening and spaced apart to correspond with spacing of letters in a line, a 130

manually carried type-carrier, comprising two series of type-bars movably mounted therein, and type on said type-bars; and means whereby when the type-carrier is depressed with any one type upon an abutment, a different type will be thrust down

between said type-guides and through said opening.
